UNITED STATES PATENT OFFICE.

EDWARD A. SCHREIBER, OF CHICAGO, ILLINOIS, ASSIGNOR, BY MESNE ASSIGNMENTS,
TO VAPOR CAR HEATING COMPANY, INC., A CORPORATION OF NEW YORK.

DEVICE FOR MANIPULATING TRAIN-PIPE END VALVES.

1,283,327.

Specification of Letters Patent.

Patented Oct. 29, 1918.

Application filed June 21, 1916. Serial No. 104,994.

To all whom it may concern:

Be it known that I, EDWARD A. SCHREIBER, a citizen of the United States, residing at Chicago, in the county of Cook and State 5 of Illinois, have invented certain new and useful Improvements in Devices for Manipulating Train-Pipe End Valves, of which the following is a specification.

My invention relates to apparatus for 10 opening and closing the angle cock or end valve of a railway car train pipe, and the principal object of the invention is to provide a simple, inexpensive and reliable device for manipulating the end valve of a 15 train pipe from the platform of the car or other point remote from the valve, so constructed as to permit the lateral movements of the end of the train pipe. On some railroad cars the ends of the train pipes are 20 not rigidly attached to the car but are free to flex for a certain distance back from the angle cock when subjected to lateral stresses, for example, as the train rounds a sharp curve; the purpose of this arrangement being to prevent the breaking of the train pipe 25 or its connections when the pipe is subjected to these stresses.

The invention consists in the novel and 30 improved constructions, arrangements and devices for carrying out the above stated object which are shown in the accompanying drawings and will be hereinafter described and claimed. It will be obvious, however, 35 that modifications might be made in mechanical details without departure from the principles of the invention which I desire to claim as broadly as the state of the art will permit.

The invention is illustrated, in certain pre- 40 ferred embodiments, in the accompanying drawings wherein—

Figure 1 is a fragmentary or sectional view taken through the end sill of a railway car, showing the usual end valve and the 45 mechanism which I have devised for manipulating the same.

Fig. 2 is a plan view of the parts shown in Fig. 1, the operating shaft being shown in section.

Fig. 3 is a sectional elevation taken on line 3—3 of Fig. 2, the scale being larger than that of the preceding figures.

Fig. 4 is a view in perspective of one member of the flexible connecting mechanism ar-

ranged between the train pipe and the shaft 55 for operating the end valve.

Fig. 5 is a sectional view on line 5—5 of Fig. 2.

Fig. 6 is a section on line 6—6 of Fig. 5.

Fig. 7 is a view similar to Fig. 2 showing 60 the extremity of the train pipe flexed so that the end valve is moved laterally from its normal position.

Fig. 8 is a sectional plan view illustrating 65 a modified form of the invention.

Fig. 9 is a view illustrating the modified construction showing, in perspective, the train pipe stirrup, a portion of the extremity 70 of the train pipe and other associated parts, and

Fig. 10 is a detail view, in perspective, of 75 the end of the operating shaft and the member slidable thereon for accommodating the device to the lateral movements of the train pipe.

Like characters of reference indicate like 80 parts in the several figures of the drawings.

Referring first to Figs. 1 to 7 inclusive, 25 designates the platform of a railway car, 26 the train pipe and 27 the usual end valve 80 or shut-off cock.

The end of the train pipe has clamped thereto a two-part shoe 28, 29, which bears upon a stirrup 30 secured to the under side of the car. The train pipe may be rigidly 85 fastened to the car by the usual hangers (not shown), the hanger nearest the end being at some distance from the end valve, so that the extremity of the train pipe may bend to a considerable extent under the 90 stresses developed when the train rounds a sharp curve. I have shown the train pipe supported so that it is self-centering, this being the common practice, the stirrup being formed with two mutually inclined members 31, and the under surface of the shoe 95 having a corresponding configuration.

32 is a shaft revolvably mounted on the car, the shaft being shown as provided with a collar 33 which bears upon the platform 25, 100 the shaft extending through a bracket 34 and being formed with a collar 35 bearing against the under side of the bracket. The lower end of the shaft 32 is secured by means of a cross pin 36 to the socket 37 of a plate 105 38 attached by screws 39 to a block 40, which is generally rectangular in cross section. The block lies within a yoke 41, the block

being preferably provided with a flange 42 projecting under the lower edges of the yoke. The yoke has a slidable, non-rotative relation with the block 40 and shaft 32. 5 The yoke is formed on one side with an arm 43 connected by a link 44 with a lever 45 having a rigid relation with the stem 46 of the valve member (not shown) of the shut-off cock 27; the shut-off cock shown being 10 of the usual type having a revolvable valve. 47 is a link lying substantially parallel with link 44 connected at one end to an arm 48 formed on a two-part clamp 49, 50 which is secured to train pipe 26. The other end of 15 the link 47 is pivoted to a bracket 51, formed on the yoke 41. The operating shaft 32 is provided with a handle 52. The shut-off valve 27 may be provided with the usual handle 53 which, however, is not used when 20 the device is manipulated from the platform of the car.

Operation: (Figs. 1 to 7 inclusive.) The shut-off cock is operated by turning the shaft 32 by means of the handle 52. The full lines 25 in Fig. 2 show the parts of the apparatus with the cock closed, the dotted lines the position of the corresponding parts when the cock is open. The sliding relation between the yoke 41 and the block 40 on the 30 end of operating shaft 32 permits the extremity of the train pipe 26 to shift transversely of the car without affecting the position of the lever 45 of the revolvable valve member of the cock. Fig. 7 shows the train 35 pipe as shifting in a direction toward the operating shaft. The connection provided by members 48, 49, 50 and link 47 transmits movement from the train pipe to the sliding yoke 41, causing the yoke to slide in the 40 direction of its length on block 40. The links 47, 44 being in substantial parallelism, the pivot points of link 44 are shifted an equal amount so that the movement of the train pipe and of the angle cock as a whole 45 does not result in any change in angular position of the lever 45 which operates the valve of the angle cock. The connections between the links are made sufficiently loose so that the links will not be cramped when 50 the end of the train pipe is raised a trifle by its movements in either direction from the central normal position of the pipe. The cock may be opened and closed regardless of the position of the end of the train pipe on 55 stirrup 30.

In Figs. 8 to 10 inclusive, I have shown the invention as embodied in a somewhat different construction. The train pipe 53 is secured by means of clip 54 to a slide 55 which is movable transversely of the horizontally disposed portion 56 of the stirrup 57 attached to the under frame 58 of a car, for example, by lag screws 59. The slide 55 is limited in its movements on the stirrup 60 by stop pins 60 and is formed with an arm

61 connected by link 62 with a clevis 63 on the end of a yoke 64 having a sliding relation with a block 65 secured to the end of operating shaft 66. 67 is a link connected at one end with the operating lever 68 of 70 the angle cock 69 and at the other end to an arm 70 on the yoke 64. The parts of the device are so proportioned that a lateral movement of the train pipe and angle cock shifts both pivotal points of link 67 an 75 equal amount so that the position of the valve of the cock is not affected by the movements of the train pipe.

I claim:

1. In combination, a train pipe of a railway car supported so that its extremity has movement laterally of the car and provided with a shut-off cock and mechanism for opening and closing the cock, comprising an operating element mounted on the car at a point remote from the cock, and connecting means between said element and cock constructed so as to accommodate itself to the lateral movements of the pipe. 80

2. In combination, a train pipe of a railway car supported so that its extremity has movement laterally of the car and provided with a shut-off cock and mechanism for opening and closing the cock, comprising an element mounted on the car to be operable 95 from the platform thereof, and connecting means between said element and cock constructed so as to accommodate itself to the lateral movements of the train pipe. 90

3. In combination, a train pipe of a railway car supported so that its extremity has movement laterally of the car and provided with a shut-off cock having a revolvable valve, and mechanism operable at a point remote from the cock for turning the valve, 100 which is constructed so as to be unaffected by the lateral movements of the train pipe. 105

4. In combination, a railway car, a train pipe supported thereon so that its extremity has movement laterally of the car, a shut-off 110 cock on the train pipe, an operating shaft revolvably mounted on the car to turn on a fixed axis, and flexible connections between the shaft and cock for opening and closing the latter, which connections are constructed 115 so as to accommodate themselves to the lateral movements of the pipe.

5. In combination, a railway car, a train pipe supported on the car so that its extremity has movement laterally of the car, a shut-off 120 valve cock on the train pipe having a revolvable valve, an operating shaft mounted on the car to turn on a fixed axis and a flexible connection between said shaft and valve for turning the valve which permits the lateral 125 movements of the train pipe to take place without affecting the position of said valve.

6. In combination, a railway car, a train pipe supported on the car so that its extremity has movement laterally of the car, a 130

shut-off cock on said train pipe having a revolute valve, an operating shaft revolubly mounted on the car, a member slidably but non-rotatably connected with the shaft, 5 and a link connecting said slidable member with the valve.

7. In combination, a railway car, a train pipe supported on the car so that its extremity has movement laterally of the car, a 10 shut-off cock on said train pipe having a revolute valve, an operating shaft revolubly mounted on the car, a member slidably but non-rotatably connected with the shaft, a link connecting said slidable member with 15 the valve, and a link connecting the slidable member with the train pipe.

8. In combination, a railway car, a train pipe supported on the car so that its extremity has movement laterally of the car, a 20 shut-off cock on said train pipe having a revolute valve, an operating shaft revolubly mounted on the car, a member non-rotatably but slidably connected with said shaft so as to be movable transversely with respect 25 thereto, and links connecting said member with the train pipe and valve respectively.

9. In combination, a railway car, a train pipe supported on the car so that its extremity has movement laterally of the car, a 30 shut-off cock on said train pipe having a revolute valve provided with a lever, an operating shaft revolubly mounted on the car, a member non-rotatably but slidably connected with said shaft so as to be movable 35 transversely with respect thereto, an arm clamped to said train pipe, a link connecting said arm with the slidable member, said slidable member being provided with an arm, and a link connecting said arm with 40 the lever of the valve.

10. In combination, a railway car, a train pipe supported on the car so that the extremity thereof is movable laterally with respect to the car, a shut-off cock on the train 45 pipe and mechanism for opening and closing the cock, comprising a shaft revolubly mounted on the car, a block rectangular in cross-section on the end of said shaft, a yoke slidably supported on the block and 50 flexible connections between the block and shut-off cock.

11. In combination, a railway car, a train pipe supported on the car so that the extremity thereof is movable laterally with 55 respect to the car, a shut-off cock on the train pipe provided with a revolute valve having a lever and mechanism for opening and closing the valve, comprising a shaft revolubly mounted on the car, a block rec- 60 tangular in cross-section on the end of said

shaft, a yoke slidably supported on the block, a link connecting the yoke with the lever of said valve and a link connecting the yoke with the train pipe.

12. In combination, a railway car, a train 65 pipe supported on the car so that the extremity thereof is movable laterally with respect to the car, a shut-off cock on the train pipe provided with a revolute valve having a lever and mechanism for opening and closing the valve, comprising a shaft revolubly mounted on the car, a block rectangular in cross-section on the end of said shaft, a yoke 70 slidably supported on the block, a link connecting the yoke with the lever of said valve, an arm clamped to the train pipe, and a link connecting the arm with said yoke.

13. In combination, a railway car, a train pipe supported on the car so that the extremity thereof is movable laterally with 80 respect to the car, a shut-off cock on the train pipe provided with a revolute valve, a shaft mounted on the car having a fixed axis of revolution, a pair of members slidably and non-rotatably engaged with each other, one 85 of which is fixed to said shaft, and mechanism comprising a pivoted link for connecting the other member with said valve whereby the pipe may move laterally without disturbing the valve.

14. In combination, a railway car, a train 90 pipe supported on the car so that the extremity thereof is movable laterally with respect to the car, a shut-off cock on the train pipe provided with a revolute valve, a shaft 95 mounted on the car having a fixed axis of revolution, a pair of members slidably and non-rotatably engaged with each other, one of which is fixed to said shaft, and mechanism comprising links independently connecting said other member with the valve and with the end of the train pipe whereby the pipe may move laterally without disturbing the valve.

15. In combination, a railway car, a train 100 pipe supported on the car so that the extremity thereof is movable laterally with respect to the car, a shut-off cock on the train pipe provided with a lever, a shaft mounted on the car having a fixed axis of revolution, a pair of members 105 slidably and non-rotatably engaged with each other, one of which is fixed to said shaft and the other of which is provided with a rigid projecting arm, a link connecting said arm with the lever of the cock, a lever having a fixed relation with the end of the train pipe, and a link connecting said element with the last mentioned slidable member.

EDWARD A. SCHREIBER.
